UNITED STATES PATENT OFFICE.

JOSHUA E. VAUGHN, OF LOS ANGELES, CALIFORNIA.

PIVOTED-CLOSURE OPERATING MEANS AND CIRCUIT CLOSER.

Application filed October 8, 1923. Serial No. 667,317.

This invention relates to mail boxes and has particular application to mail boxes of the type used on rural routes.

The invention has for its object the provision of a box equipped with mechanism adapted to be actuated by the carrier when delivering or depositing mail within or on the box, and which mechanism sounds a signal and also operates an indicator arranged 10 within the house, thus informing the occupant thereof that the mail has been delivered.

In carrying out the invention, I also provide a switch arranged within the house, and connected in circuit with a signal supported on the box, so that the said signal can be sounded at the will of the owner, the signal being used to inform the letter carrier that the occupant of the house desires to speak to him.

The nature and advantages of the invention will be better understood when the following detailed description is read in connection with the accompanying drawings, the invention residing in the construction, 25 combination and arrangement of parts as claimed.

In the drawings forming part of this application, like numerals of reference indicate similar parts in the several views, and 30 wherein:

Figure 1 is a view in elevation of the mail box and the instrument board adapted to be arranged within the house.

Figure 2 is a vertical sectional view 35 through the mail box showing the parts in normal position.

Figure 3 is an end elevation of the mail box partly in section.

Figure 4 is a detail view of the combined 40 door operating means and circuit closer.

Referring to the drawings in detail, 10 indicates generally a mail box which can vary in size and configuration without departing from the spirit of the invention.

45 The box including at one end an auxiliary box or compartment 11 adapted to receive mail deposited by the owner and to be collected by the mail carrier. The construction and manner of using this auxiliary box 11 will be hereinafter more fully described.

The box 10 is utilized to receive mail delivered by the carrier, and has a receiving

slot 12 normally closed by a pivoted door 13. The box is also equipped with means for clamping mail on the top of the box, this means being utilized to clamp papers, packages or the like which are too large to be inserted through the slot 12. The means for this purpose consist of a frame made up of inverted U-shaped members suitably spaced apart, and which members have their parallel links 14 and 15 respectively depending through the top of the box and slidably through openings formed therein. The cross bar 16 of each U-shaped member is arranged above and parallel with the top of the box, the mail matter being clamped between the top and these cross bars 16. The U-shaped members are connected together by a transverse bar 17 arranged adjacent the box and it will also be noted that the corresponding limbs 16 of these U-shaped members are slightly longer than the limbs 14 to extend an appreciable distance within the box, the limbs 15 being connected at 70 their lower ends by a cross member 18. This clamping device is normally maintained in a lowered position as illustrated in the different views in the drawings, by means of a coiled spring 19 housed within a suitable 80 casing 20 secured to the rear wall of the box 10. A wire element 21 connects the upper ends of this spring with the cross member 18 of the clamping frame and normally exerts downward pressure on the latter, this cross member 18 however, is also connected with the adjacent end of a flexible cable 22 the latter being trained over an idle pulley 23 journalled in a suitable bracket 24 secured to the rear wall of the box 10 immediately above and in alignment with the spring 19. The other end of this cable is connected with a lever 26 pivoted at an appropriate point in its length as at 27, the other end of this lever being connected with a vertically movable operating rod 28. The lower end of this rod is in turn connected with the adjacent end of a manually operable lever 29 pivoted within the box as at 30, but extending exteriorly of the box and equipped with a handle 31. When it is desired to arrange the papers or packages beneath the clamping frame, it holds said articles immovable upon the top of the box,

it is only necessary to depress the lever 29, thereby elevating the rod 28 which of course rocks the lever 26 upon its pivot. The lever is rocked in a direction to move the flexible cable 22 over the pulley in a direction to move the clamping frame a sufficient distance above the top of the box to allow the packages and papers to be arranged in a manner above described. When the lever 29 is released, the spring 29 functions to move the clamping frame downwardly to its active or clamping position, and incidently return the lever 29 to its normal position or substantially so. This mechanism is supported in an electric circuit, which embodies a signal 32 in the nature of a bell so that the occupant of the house will be informed each and every time mail is delivered. The lever 26 constitutes a movable contact, adapted to engage a fixed contact 33 when the mechanism is operated to elevate the clamping frame above described. This consequently closes the circuit to the bell 32, the current passing from the battery 34 through the wire 35, to a switch 36 mounted upon the instrument board 37 arranged within the housing, and thence passing through the signal or bell 32 to the wire 38, and thence through the lever 26 and fixed contact 33 to the return wire 39 which leads back to the battery 34 to one of a pair of electro-magnets. As the current passes through the magnet just referred to and indicated at 40, the pointer or indicating finger 41 is moved from its normal position shown in both Figures 5 and 6 to an active position, in which position it points in the direction of the word "Mail" arranged on the face of the instrument board 37. The electro-magnet 40 is energized for this purpose being included in the circuit just described, although the pointer or indicator finger 41 can be conveniently reset, or returned to normal position by energizing the other electro-magnet included in a circuit independently of the circuit just described, and which circuit also embodies a push button 43 mounted upon the instrument board 37. When the push button 43 is operated, the current passes from the battery 34 through the wire 44 to the electro-magnet 42, energizing the latter for the purpose just mentioned, the current passing from the magnet through the wire 45 to the push button switch 43, and thence through the wire 46 which is a return wire connected to the wire 35 terminally associated with the battery. This circuit can be closed at any time that it is desired to return the pointer to its normal or inactive position, whether the latter has been moved to an active position by energizing the circuit including the lever 20, or energized by the independent circuit which is closed incident to the opening of the door 13 of the mail box proper.

In this connection it will be noted that I have devised a mechanism for opening the door 13, and simultaneously closing the electric circuit to the signal 32, so as to inform the occupant of the house that mail matter 70 has been deposited in the box. The means employed for this purpose embodies a shaft 47 which has connected thereto one of a pair of spaced parallel links indicated at 48 and 49 respectively, these links being connected at their corresponding upper ends by a link 50 while also associated with the lower end of the link 49 is a link 51 arranged parallel with the link 50. These links defining a parallelogram, with the link 48 considerably 80 shorter than the link 49 and directly connected with the shaft 47. The link 49 is also mounted on a pivot 52 which is suitably mounted within the mail box 10. Depending from the shaft 47 are spaced parallel arms 85 53 from the lower extremities of which extend arms 54. These arms 54 are arranged substantially at a right angle to the arm 53, and project in the direction of the floor 13 with which they are pivotally connected as 90 55. Depending from the link 51 of the parallelogram is an arm 56 which is also mounted on a pivot 57, this arm being pivotally associated with the link 51. The lower end of the arm 56 supports a contact 58 included in an electric circuit which is closed simultaneously with the opening of the door 13 in a manner to be presently described. Mounted upon the mail box for sliding movement is a spring pressed rod 59 which 100 projects an appreciable distance from the front of the box and equipped with a knob or handle 60 so that it can be conveniently operated. This rod slides through a casing 61 arranged within the box, and which casing houses a spring 62 which normally holds the rod in the position shown in Figures 2 and 6. The inner end of this rod carries a contact 63 forming with the contact 58, a circuit closer for the purpose above specified. 110 These contacts are normally spaced apart, but when the rod 59 is pushed inwardly for the purpose of opening the door 13, inasmuch as the parallelogram above described is actuated to move the arms 54 outwardly, a contact 63 is brought into engagement with the contact 58, thereby closing the said circuit to the signal 32. In the circuit just referred to, the current flowing from the battery through the wire 64 to the electro-magnet 40, which of course moves the pointer or indicator finger to an active position as above described. The current passes from this magnet through the wire 39 to the circuit closer including the contacts 58 and 63 respectively, from where it passes through the wires 65 and 38 to the signal 32. The signal is then sounded for the purpose above mentioned, the current passing from the signal through the switch 36 and then back to the 120 130

battery through the wire 35. When the rod 59 is released, the spring 62 returns the parts to normal position, thus breaking the circuit as will be readily understood, and incidently 5 closing the door 13.

From the structure thus far described, it is manifest that the signal 32 will be sounded when mail matter is either deposited within the box 10, or clamped on the top of the 10 box through independent circuits, and independent operating means. However, the switch 36 which is mounted upon the instrument board within the house must be closed in order to complete either of the circuits described. Consequently if for any reason, the 15 occupant of the house should not want the signal 32 sounded under any circumstance, it is only necessary to open the switch 36. It might be stated that the instrument board 20 37 can support any number of useful articles such as a barometer 66 and a thermometer 67, while arranged at some appropriate part of the board is an electric light bulb 68. This bulb of course is included in the house 25 circuit controlled by an independent switch and utilized to illuminate the board at any time desired. The indicator above referred to is indicated at 69 and consists of a small 30 piece of material having the word "Mail" arranged thereon, the pointer 41 forming part of the indicator generally. In the lower corner of the board is a clock 70, while arranged above the clock is a mirror 71.

As above stated, the invention also provides means whereby the attention of the mail carrier can be attracted thus informing him of the fact that the occupant of the house desires to speak to him, and this mechanism includes a signal in the nature of a bell indicated at 72. The bell is mounted upon the mail box 10, and is included in circuit with a push button switch 73 also mounted upon the instrument board 37. When the push button is operated, the current flows from the battery through the wire 35 to the signal 40 72, passing from the signal through the return wire 74, through the switch 73 and thence back through the battery, through the wires 75 and 76 respectively. It will be noted that the circuit can be energized to 45 sound the signal 32 independently of the switch 36, which as just stated must be closed for the completion of another circuit.

The auxiliary box 11 which is arranged 50 on one side of the main box 10 is adapted to receive mail matter to be collected by the carrier, and this box includes a hinged cover 77. The cover has secured thereto an angular shaped bar, one portion 78 extending 55 across the cover and secured thereto, while the other portion 78 of this rod depends from the cover and terminates to provide a hook like extremity 80. Supported by the front of the box is a small casing 81 which 60 contains a circuit closer. This circuit closer

includes a plurality of spaced roller contacts indicated at 82, 83 and 84 respectively, there being preferably three of such contacts adapted to be alternately engaged by a movable contact 85 carried by a shaft 86, 70 and adapted to be rotated in order to release the cover 77 so that mail matter deposited in the box can be removed by the carrier. Also carried by this shaft 86 exteriorly of the casing 81 is an arm 87 which is adapted 75 to be received by the hook like extremity 80 and thus hold the cover in a closed position, and necessitating the rotation of the shaft 86 before the cover can be opened. Carried by one end of this arm 87 is a sign 88 which 80 contacts the words "Stop for mail please". Obviously, when the shaft 86 is rotated incident to the removal of the arm 87 from the hook like extremity 80 of the rod 79, the movable contact 85 of the circuit closer is 85 successfully brought into engagement with the spaced contacts 82, 83 and 84, thereby intermittently closing the circuit which also includes the signal 32, with a resultant sounding of the signal three distinct times. 90 This informs the occupant of the house that the mail deposited in the box 11 has been collected by the carrier, the sounding of the signal three times differentiating the use of the signal for this purpose, as compared to the sounding of the signal once, which of course occurs when mail is delivered, by either depositing the mail within the box 95 10 or clamping the mail on the top of the box as described. When the circuit is closed intermittently as stated, the current flows from the battery 34 through the wire 76 which is connected with the fixed contacts 82, 83, and 84 and as the movable contact 85 engages these fixed contacts, the current 100 flows through said movable contact through the wire 89, and thence through the wire 38, through the signal 32, sounding the latter every time the movable contact engages one of the fixed contacts. The current passes 105 from the signal through the switch 36 back to the battery through the wire 35.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

The combination with a receptacle having a pivoted closure, of a transversely arranged shaft within the receptacle, a plurality of pivotally connected links arranged to provide a parallelogram vertically disposed within the receptacle, one of the vertical links being connected with said shaft, arms depending from said shaft, arms projecting 125 130

forwardly from the aforementioned arms and connected with said closure, a lever depending from the lowermost horizontal link and pivoted between its ends, an electric contact supported by said lever, a sliding plunger mounted on the front of the receptacle and movable within the latter, and an elec-

trical contact carried by the plunger and adapted to engage the first mentioned contact to operate said shaft for the purpose 10 specified.

In testimony whereof I affix my signature.

JOSHUA E. VAUGHN.
